NOMUS PETERS, INC. www.nomus.com

UNITED STATES PATENT OFFICE.

FRITZ L. ANDREN, OF CHICAGO, ILLINOIS, ASSIGNOR TO S. KARPEN & BROS., OF CHICAGO, ILLINOIS, A CORPORATION OF WEST VIRGINIA.

FOLDING COUCH.

1,155,779.

Specification of Letters Patent.

Patented Oct. 5, 1915.

Application filed July 2, 1913, Serial No. 776,897. Renewed May 26, 1915. Serial No. 30,663.

To all whom it may concern:

Be it known that I, FRITZ L. ANDREN, a citizen of the United States, and a resident of the city of Chicago, in the county of Cook and State of Illinois, have invented certain new and useful Improvements in Folding Couches; and I do hereby declare that the following is a full, clear, and exact description of the same, reference being had to the accompanying drawings, and to the numerals of reference marked thereon, which form a part of this specification.

A great many folding couches have been constructed with a revoluble seat mounted upon companion plates attached to the couch frame, the seat guided in suitably shaped cam slots or grooves. Such constructions are open to certain objections for the translatory movement of the seat is limited by the length of the slots in the companion plates and very often this is undesirable, inasmuch as it is sometimes necessary to move the seat frame a certain distance during the rotational movement thereof in order that the seat frame when moved to such position may afford a means of support for a sectional mattress frame connected thereto.

By my invention the objections to constructions involving the use of companion plates are obviated by connecting the seat frame to the couch frame by a series of links which, due to the operation and disposition of the sectional mattress frame, permit easy operation of the device into open or closed position, due to the balanced arrangement of the elements.

It is an object of this invention to construct a folding couch provided with a revoluble seat frame and a sectional mattress frame connected thereto and to the couch frame adapted to be elevated into extended position when the seat frame is rotated from normal position.

It is also an object of this invention to construct a folding couch having a sectional foldable mattress frame adapted to be folded beneath the seat frame of said couch and suitably arranged links connecting said seat frame to said couch frame to permit easy and proper manipulation thereof.

It is also an object of this invention to

provide a folding couch having a plurality of mattress frame sections mounted thereon and with a revoluble seat linked to the couch frame and acting during the revolution thereof to operate said sectional mattress frame members into extended or folded position.

It is also an object of this invention to provide a folding couch equipped with a sectional mattress frame, one section of which is pivotally mounted upon the couch frame and another upon the seat frame and in which the inner end of the mattress frame tracks upon suitable guide members during the folding or unfolding operation of the device.

It is also an object of this invention to construct a folding couch, the seat frame of which is linked to the couch frame, together with a sectional mattress frame partly supported upon links connected to the seat frame, and to the couch frame, together with positively actuated means adapted to lock in position to support the mattress frame.

It is also an object of this invention to construct a folding couch provided with a revoluble seat frame having a linked connection connecting said seat frame and said couch frame, together with a foldable sectional mattress frame adapted to be elevated into extended position when the seat is inverted from normal position, and with connected pairs of supporting links secured to the seat frame and the couch frame.

It is furthermore an object of this invention to construct a folding couch wherein a rotational seat is linked to the couch frame and a sectional mattress frame foldable therewith, together with resilient means connected to the couch frame and to the folding mechanism to assist in opening and closing the device.

It is finally an object of this invention to construct a device in which the linked mechanism folds in a manner to balance the device in all its positions, thereby facilitating opening and closing of the same.

The invention (in a preferred form) is illustrated in the drawings, and hereinafter more fully described.

In the drawings: Figure 1, is a top plan

view of a device in extended or unfolded position. Fig. 2, is a side elevation thereof with parts removed. Fig. 3, is a similar side elevation with the outer section of the mattress frame folded. Fig. 4, is a similar elevation illustrating the operation of folding. Fig. 5, is a side elevation illustrating the device in folded or normal position, with certain parts omitted. Fig. 6, is a front elevation of the seat frame when the same is in inverted position and supported upon the gravity legs. Fig. 7, is a fragmentary detail partly in section illustrating the connection between the mattress frame and the seat frame. Fig. 8, is a fragmentary top plan view illustrating the linked connection between the seat top and the mattress frame. Fig. 9, is a detail showing the relation of the pivotally connected links connecting the seat frame and the couch frame, a portion of each of which is shown in dotted lines. Fig. 10, is a fragmentary rear elevation of one end of the couch frame when the mattress frame is in extended position. Fig. 11, is a fragmentary section taken on line 11—11 of Fig. 1. Fig. 12, is a side elevation of a modified form of a device illustrating the relation of the parts during a folding operation. Fig. 13, is a side elevation of a portion of the mattress frame, showing in dotted lines the position assumed by certain of the elements during a folding operation. Fig. 14, is a top plan view thereof.

As shown in the drawings: a couch frame 35 is denoted as a whole by the reference numeral 1, and is provided as usual with an upholstered back 2, and a front base board 3. The seat or seat frame 4, is suitably linked to the couch frame by means of a bracket 5, secured on the inner surface of the base board 3, and a pair of links 6, and 7, at each end of the seat frame, the latter of which is pivotally connected to a bracket plate 8, secured upon the interior surface 45 of the side walls at each end of the seat frame. Another pair of links numbered as 9 and 10 respectively are pivotally connected together and at their ends also in the respective bracket plates 5, and 8, before mentioned. A pivot pin also connects the links 7, and 9, of the respective pairs, together. This linked connection serves to properly elevate the seat frame during a rotational movement thereof, such as disclosed in Fig. 55 4, the position of the particular links already mentioned for this position of the seat frame, being shown in detail in Fig. 9.

The foldable mattress frame consists of the main sections 11, 12, and 13, linked 60 together by the intermediate sections 14, and 15. Each side of the mattress frame is supported at four points, each of the sections 12, being pivotally mounted on the under side of the seat frame. The mattress

frame is also supported at the junction between the members 11 and 14, by means of an angled pivot member 11^a, which is pivotally mounted in a bracket on the couch frame and also a link 17, which is pivotally mounted on the upper end of said bracket 70 plate 5, upon the same pivot to which the link 9, is connected.

For the purpose of moving the respective members 11, 11^a, 14, and 17, into elevated position, a connecting rod 18, is connected 75 upon the common pivot member 11^a, and at its other end is pivotally connected to the arm of the bell crank 16, so that as the section member 12, is extended into proper horizontal position the members 11, and 14, 80 are also alined therewith, being drawn upwardly into such position by the connecting rod 18, and supported by the pivot member 11^a, and 17. The outer extremity of the mattress frame is adapted to be supported 85 by a leg 19, which is provided with a curved extended portion 20, having a notch therein, said portion being linked to said member 15, by means of a pivotally mounted connecting bar 21. The purpose of the notch is to engage 90 the pin 22, secured on the section 12, when the outer section 13, is folded.

The other end of the mattress frame, or the inner extremity of said section 11, is provided with a pin 23, which tracks 95 respectively upon the horizontal and inclined angle bars 24, and 25, secured on the inner surface of the end posts of the couch frame.

When the device is in folded position said pin 23, rests upon the flange of the lower 100 angle bar 24, and during the operation of unfolding tracks rearwardly thereon and after being elevated and with the continued unfolding of the mattress frame, tracks forwardly and upwardly upon the inclined 105 angle bar 25, being limited in its movement thereon by the hook 26, formed integral with said bar 25. Thus when the mattress frame is extended it is supported at four 110 points at each side thereof, such supports comprising the guide plate 25, links 16, and 17, and pivot member 11^a, together with the positively actuated leg 19. When the seat frame is in a revolved position with the mattress frame extended the rear portion of 115 said seat frame is supported upon the floor by the pivoted gravity acting legs 27, which fall into position automatically and rest upon the floor when the seat frame is so revolved.

For the purpose of assisting in opening and closing the device and to balance the weight thereof, a spiral tension spring 28, is secured at one of its ends at a fixed point near the back of the couch frame, and the other end of said spring is connected to a pivoted lever 29, which is connected upon the pivot pin in the upper end of the bracket 120 125

plate 5. When the mattress frame is folded and the seat frame returned to normal position the pivot member 11^a, strikes said pivoted lever 29, and bears downwardly thereon, 5 thus supporting the mechanism against the tension of said spring 28, and when the seat is finally returned to normal position said lever 29, is directed downwardly and outwardly, and held in such position against 10 the tension of said spring by the weight of the folding mechanism thereon.

The lower connected ends of the supporting legs 19, are provided with a strap 30, which is provided with a loop adapted to 15 engage on a button 30^a, secured on the rear side of the seat frame when the respective sections 12, 13 and 15, have been folded inwardly, said strap serving to prevent the linked mechanism from falling away from 20 the seat frame when the same is turned into normal position, and also insuring a positive movement therewith when the seat is inverted for the purpose of extending the mattress frame.

25 In the modifications illustrated in Figs. 12, 13, and 14, the locking pin 22, has been dispensed with, and in its place the link 14, has been supplied with a triangular shaped web member 31, and instead of the notch in 30 the portion 20, of said leg 19, the extremity of said portion is turned inwardly substantially at a right angle as indicated by the reference numeral 32, so that as the mattress frame is folded as shown in Fig. 13, said 35 inturned member 32, rides upon the section 12, until the junction with the link 14, is broken; said inturned portion 32, then engages over the edge of said web member 31, said portion 20, being confined between said 40 web and said connecting rod 21, thus preventing the outer mattress frame section from falling away from the seat frame as the same is returned to normal position.

45 The respective mattress frame sections 13, on each side of the device are connected integrally or otherwise by an end frame member 33, and a similar member 34, connects the respective sections 11. A wire spring 35, adapted to support a mattress, is connected at intervals to the respective link members of the foldable mattress frame, and of course, due to its flexible nature, in no way interferes with the folding or unfolding of the device.

50 The operation is as follows: When it is desired to open the device the operator seizes the projecting end of the strap 30, which, as shown in Fig. 5, is caught between the back 2, and the seat 4, and pulling outwardly and 55 upwardly thereupon, causes the seat frame to rotate about the various pivot points in the linked connections existing between said frame and the couch frame, and carrying the associated mattress frame sections therewith.

This rotation of the seat frame also causes an 65 elevation of the sections 11, which track upon the respective angle irons 24, and 25, until as the seat is completely inverted and supported upon the gravity legs 27, a continued extension of the mattress frame sections 70 will automatically bring the sections 11, into alinement with the other sections in a substantially horizontal plane. The spring 28, which is normally under tension when the device is in normal position, greatly assists in opening the device and serves to balance the mechanism in its most unstable position or when the seat frame is directed upwardly from the couch frame, and is moving to or from the same, but when the device is 80 completely unfolded and the pivot members 11^a, have swung out of contact with the levers 29, the spring is under no tension. When it is desired to fold the device the end frame sections 13, are moved upwardly and 85 inwardly and the notch in the portion 20, of said leg 19, is latched upon the pin 22, in the section 12, the folding movement serving to retract the supporting leg 19, into a 90 position parallel and adjacent said sections 13. The strap 30, is then looped over the button 30^a, upon the seat frame, and the seat frame thereupon inverted into the dav-enport frame, such movement causing the gravity legs 27, to automatically fall rearwardly into a position adjacent and parallel 95 to the rear surface of said seat frame.

In the modifications disclosed in Figs. 12, 13, and 14, in place of the notched portion 20, a lip or flange 32, is provided on the extremity of said portion which engages around the edge of the web plate 31, and thus serves to retain the outer end and intermediate linked sections of the mattress frame in folded relation when the seat frame 105 is reverted to normal position.

I am aware that various details of construction may be varied through a wide range without departing from the principles of this invention. I therefore do not 110 purpose limiting the patent granted otherwise than necessitated by the prior art.

I claim as my invention:

1. In a device of the class described a couch frame, a seat frame, bracket plates 115 on each of said frames, a pair of links pivotally connected together and connecting the lower end of one of said bracket plates with the upper end of the other of said bracket plates, another pair of links pivoted together connecting the upper end of one set of said bracket plates with the lower end of the other bracket plates, a pivot connecting said pairs of links together, a link pivoted on the couch frame, a spring connected to 120 said link and to the couch frame, a sectional mattress frame adapted to be extended when said seat frame is rotated and inverted rela-

tive to said couch frame, and, when returned to folded position with said seat in normal position, supported on said links against the tension of said spring.

5. 2. In a device of the class described a couch frame, a seat frame, a plurality of pairs of links connecting said frames at each side thereof, a common pivot connecting said pairs of links one to another, a foldable mattress frame connected to said couch and seat frames adapted to be extended when said seat frame is rotated and inverted relative said couch frame, and a plurality of separate tracking members for the rear portion of 10 said mattress frame.

15. 3. In a device of the class described a couch frame, a seat frame, pivotal connections therebetween permitting rotational movement of said seat frame relative said 20 couch frame, a sectional mattress frame connected on said couch and seat frames, a plurality of bracket plates secured on said couch frame, an angled supporting member connected to one of said bracket plates and 25 to one of said mattress frame sections, and a plurality of links connected between said couch frame and said seat frame to properly govern the movement of said seat frame in its rotational movement about said couch 30 frame, one of said links connected to the mattress frame at the same point as said angled supporting member.

35. 4. In a device of the class described a couch frame, a seat frame, a plurality of pairs of links on each side thereof connecting said frames together, a common pivot connecting each of said pairs of links together, a foldable sectional mattress frame connected to said seat frame and to said 40 couch frame, actuating links and angled pivot members connected to said seat frame and to said mattress frame to properly position the same when extended and support the same upon said seat frame, and a positively 45 actuated leg connected on the outer end of said mattress frame to support the same upon the floor.

5. 5. In a device of the class described a couch frame, a seat frame, a foldable mattress frame associated therewith, a positively actuated leg connected on the end of said mattress frame, a pin in one of said mattress frame sections, a notched extended portion integral with said positively actuated 55 legs adapted to engage said pin to lock the outer mattress frame sections together in folded position, a button on said seat frame, and a flexible strap connected to said positively actuated legs adapted to engage said 60 button to retain said mechanism in folded relation upon said seat frame.

6. 6. In a device of the class described a couch frame, a seat frame linked thereto, a foldable sectional mattress frame associated

therewith, a plurality of tracking members 65 adapted to support and guide one end of said mattress frame, in folded and extended positions respectively, connected links adapted to support said mattress frame sections upon said seat frame when the same is inverted, and a positively actuated leg connected to the end of said mattress frame section to support the same upon the floor when the mattress frame is extended.

7. In a device of the class described a couch frame, a seat frame, pivotal connections between said seat and couch frames, a folding mattress frame connected on said seat and couch frames and adapted to be extended when said seat is rotated from said couch frame, a plurality of horizontal and inclined tracking members to guide and support the rear portion of said foldable frame, and resilient means connected within the couch frame to receive the weight of the parts thereon when the same are folded and the seat is returned to normal position.

8. In a device of the class described a seat frame, a couch frame adapted to support the same, pivotal connections between said two frames, a sectional mattress frame connected to said couch frame and to said seat frame adapted to be extended when said seat frame is rotated from within said couch frame to a point in front thereof, means supporting one end of said seat frame upon the floor when in rotated position, a plurality of horizontal and inclined tracking means for the rear portion of said mattress frame, a lever and spring connected to one another and connected within said couch frame to receive the weight of the parts thereon when folded and returned to normal position, radius links connected to said couch frame and to said mattress frame adapted to project the same upwardly when the same is unfolded, a positively actuated leg connected on said mattress frame adapted to be extended and retracted with movement of the mattress frame section, and means on said leg and on a portion of said mattress frame to interlock with one another to retain the parts in folded position when the device is returned to normal.

9. In a device of the class described a couch frame, a seat frame, a sectional mattress frame connected to said couch and seat frame, links connected between said couch and seat and mattress frame adapted to permit rotational movement of said seat frame and extension of said mattress frame, radius links and inclined pivot members connected on said couch frame and to certain of said mattress frame sections to project the same upwardly into alined position when the device is extended, resilient means connected entirely within the couch frame adapted to receive the weight of the parts thereon when

the same are folded and returned to normal and unstressed by the mattress frame or seat when the parts are extended, and means on said mattress frame adapted to interlock with said seat frame to hold the parts there-
to when the same are returned to normal position.

In testimony whereof I have hereunto sub-
scribed my name in the presence of two sub-
scribing witnesses.
